ATTORNEY.

UNITED STATES PATENT OFFICE.

WILLIAM C. P. BALDWIN, OF HOLYOKE, MASSACHUSETTS, ASSIGNOR TO BALDWIN GARMENT COMPANY, OF HOLYOKE, MASSACHUSETTS, A CORPORATION OF MASSACHUSETTS.

WOMAN'S REVERSIBLE-FRONT HOUSE-DRESS.

1,039,632.

Specification of Letters Patent. Patented Sept. 24, 1912.

Application filed April 27, 1912. Serial No. 693,665.

To all whom it may concern:

Be it known that I, WILLIAM C. P. BALDWIN, a citizen of the United States of America, and resident of Holyoke, in the county of Hampden and State of Massachusetts, have invented certain new and useful Improvements in Women's Reversible-Front House-Dresses, of which the following is a full, clear, and exact description.

10 This invention relates to improvements in a woman's house dress of a kind comprising waist and skirt portions, one of which is continuous with the other, and either skirt and waist portion being adapted to overlap the other so as to be, as elected, worn outermost, together with means located at the waist line for fastening the inwardly disposed skirt and waist portion relatively to the side of the garment body and also means 20 for the securing of the edge portion of the externally disposed skirt and waist portion to the opposite side of the garment body.

The object of the invention is to provide a simple and inexpensive garment of the 25 character described with provisions for the fastening of the reversible front forming portions thereof for a convenient and easily manipulated garment.

The invention is described in conjunction 30 with the accompanying drawings and is defined in the claims.

In the drawings:—Figure 1 is a front view of the house dress as worn. Figs. 2 and 3 are horizontal sectional views taken at 35 the waist line, that is as indicated by line 2—2, Fig. 1, these views being similar in character but showing reversed relations of the front forming portions of the garment and reversed arrangements of the fastening means therefor.

In the drawings, A represents the body of a house dress, the front forming portions B and B² comprising therein waist and skirt portions a and a², one continuous with 45 the other and of similar form so that one will overlap the other and each extend from the side of the body across the front and around to the opposite side. Each front forming portion has a buttonhole b therein 50 near its free edge at the waist line, and the garment has through the body portion thereof at the waist line and at opposite sides of such body portion slotted openings d d there- through.

f f represent comparatively short tabs 55 secured by stitching to the garment body adjacent said slotted openings d d, each adapted to be positioned either outside of the garment body or by insertion through the adjacent slotted opening to a position 60 inside of such body. Each tab toward or near its free end is provided with a button hole e.

Now on reference to Fig. 2 it will be seen that the garment front B is lapped across 65 and overlies the other garment front forming portion B², the tab f at the left being externally positioned and the buttonhole in the free left hand edge of the overlapped front B matches with the buttonhole in the 70 tab, and a fastening stud g is matched through the buttonhole b of the dress front and the buttonhole e in the tab for detachably securing the jointed portions together. And in the same view, Fig. 2, it will be 75 perceived that the tab f at the right hand of the garment is inserted through a slotted opening d and is internally disposed and with the buttonhole b thereof matches the buttonhole b at the free edge of the garment 80 front B² and through these coinciding buttonholes a second stud g is engaged so that the edge portions of the underlying and the overlapped dress fronts are secured or stayed at oppositely located positions about 85 where the front merges into the back. Now on reference to the other view, Fig. 3, a reversal of the arrangement is shown, the dress front B being innermost and the one B² being outermost, the left hand tab f being internally located, while the right hand tab f is drawn to the outside, and the connections are perfected by the detachable studs in similar manner to that represented in Fig. 2.

D represents a band to form a portion of a belt which extends around the rear portion of the garment, the same here being represented as formed in two parts h and h², one overlapping the other at the back and 100 adapted to have a take-up capability and to be secured by glove snap fastenings z as here represented, although not necessarily so, as it is the forward end portions of these belt bands h, h² which constitute the aforementioned tabs f f. Crossing on the face of each of the dress front forming portions B and B² are further belt forming bands or

sections j and j^2 , the same being secured at their opposite ends by the stitching h against detachment. These belt bands j and j^2 near their ends at the free edges of 5 the dress fronts have buttonholes therein which coincide with the buttonholes b so that the studs, when the parts are secured, may be engaged therethrough although, if desired, the studs need not be passed through 10 the ends of these belt forming bands, but only through the buttonholes b , and may be concealed by the belt bands.

I claim:-

1. A reversible house dress the body of 15 which at the front is made with waist and skirt portions, one continuous with the other, and either skirt and waist portion being adapted to overlap the other, and said garment at the waist line at opposite sides 20 thereof having slitted openings therethrough, and a short tab secured to the garment adjacent each slitted opening, and adapted to be positioned either outside of the garment body, or by insertion through 25 the slitted opening inside of such body, fastening means, cooperative between the said tabs and the edge portions of the reversible front portions for securing the overlapping front portion to an externally positioned tab, 30 and for securing the inwardly disposed front portion to the other, and internally positioned tab.

2. A reversible house dress the body of which at the front is made with waist and skirt portions, one continuous with the other 35 and adapted for overlapping relations and said garment at the waist line, at opposite sides of the body portion, having slitted openings therethrough, a belt band at the rear of the garment having opposite portions thereof stitched to the garment body adjacent the said slitted openings and having comparatively short tabs extending beyond said stitched portions and adapted to be positioned either outside of the garment 40 body or by insertion through the slitted openings inside of such body, said tabs and the reversible front forming portions near their free edges having buttonholes therein, belt forming bands stitched to the garment 45 body adjacent but forward of said slitted openings and having buttonholes therein to match with those of the reversible garment front portions and studs engageable through the buttonholes in the said tabs and in the 50 edge portions of the reversible front portions and in the belt bands for the purpose set forth.

Signed by me at Springfield, Mass., in presence of two subscribing witnesses.

WM. C. P. BALDWIN.
